UNITED STATES PATENT OFFICE.

LELAND L. SUMMERS, OF CHICAGO, ILLINOIS.

COKE-OVEN.

1,155,526.

Specification of Letters Patent.

Patented Oct. 5, 1915.

Application filed May 22, 1914. Serial No. 840,171.

To all whom it may concern:

Be it known that I, LELAND L. SUMMERS, a citizen of the United States, residing in Chicago, county of Cook, and State of Illinois, have invented new and useful Improvements in Coke-Ovens, of which the following is a specification.

The object of my invention is to provide an improved coke oven of the general type shown in my prior Letters Patent No. 943,610 of December 14th, 1909, in which carbonaceous material is fed to a horizontal retort at one end and conveyed through the retort by means of a reciprocating floor, the treated material being discharged at the other end of the retort.

Among the features of construction and operation is the provision of means for causing the compression produced within the retort by the operation of the conveyer floor to be more uniformly transmitted through the material to the walls of the retort, and also the provision of means for distributing the heat throughout the material in the retort so as to produce a more uniform plastic or semi-plastic condition in the material so that when compression is applied the plastic or semi-plastic portion of the material may be more readily subjected to this compression in a more uniform manner. In order to accomplish this result, I construct my retort with side walls and sub-divide the retort by means of intermediate walls, the side and intermediate walls being provided with heating ducts, as is also the arch or roof of the retort.

In the drawings, Figure 1 shows a longitudinal section of my apparatus. Fig. 2 is a transverse section on the line 2 of Fig. 1. Fig. 3 is a plan view of a portion of the retort at the charging end thereof.

While I have illustrated in detail structures embodying my invention, it will be obvious that the particular form shown may be varied without departing from my invention.

Referring to Fig. 2, A represents the longitudinal side walls of a horizontal retort, these retorts being built in groups, or batteries, as may be desired. Each retort is sub-divided by one or more longitudinal partition walls C, which preferably are of lighter construction than the side walls, thus dividing the retort into a number of cells extending throughout the length of the retort. Along the side walls are arranged a

series of tiles B formed with heating ducts B' extending the length of the retort and the partition walls C are likewise provided with longitudinally extending heating ducts C'. The arch or roof of the retort, which is supported by the side walls and the intermediate walls, is formed of tiles B² also provided with longitudinally extending heating ducts B²'. Within each cell of the retort is arranged a longitudinally movable floor D which is of fire resisting material, and this floor is provided upon its under side with tracks D² which travel upon anti-friction rollers D⁴ mounted in suitable bearings D⁶ fixed in the foundation. Along each edge of the floor is arranged a downwardly extending lip D', which extends into a channel D² which runs longitudinally of the retort at the lower portion of the side wall beneath the floor. A cooling pipe D⁶ may be placed beneath this channel if so desired. The floors D² of each retort are connected at the charging end of the retort by a cross head E, and this cross head is suitably connected to the hydraulic ram F, so that a single ram F will operate the floors of all the cells of a single retort. The carbonaceous material is fed to the reciprocating floor from the bin H and is discharged into a suitable discharging chamber K, as is more fully described in my patent hereinbefore referred to, that is to say portions of fresh material are charged into the oven upon the forward movement of the reciprocating floor as described in this patent.

G indicates the pipe adjacent the charging end of the retort for withdrawing the products of distillation which are passed through the hydraulic main G', which is of the ordinary and well known construction. It is obvious that the pipe G may be arranged so as to withdraw the products of distillation from any desired point in the retort.

L represents the regenerator and L' the regenerator valve arranged as is usual.

Generally speaking, the operation of feeding carbonaceous material to the retort is as described in my prior patent. The material which is received upon the floor D from the coal bin H is moved into the retort by the reciprocating floor as the floor is advanced into the retort by the ram F. When the floor is drawn outward, the material within the retort is prevented from moving outward by means of the stripper comprising

the outer wall of the coal bin, the action of this stripper being to restrain the coal from moving with the floor, thus causing the floor to be withdrawn from the retort while the coal 5 is prevented from being so withdrawn. This causes a pressure to be exerted on the material in the retort tending to move it backward. This exerts a pressure on the stripper, and this pressure is transmitted to the material 10 in the retort, causing it to be compressed. The adhesion of the material to the floor of the conveyer caused by frictional contact between the material and the floor may be made to exert a very heavy pressure upon 15 the stripper, which in turn causes these pressures to act upon the material on the conveyer floor within the retort. In order to have this pressure on the portion most effective in modifying the physical characteristics 20 of the material, the material should be heated to a plastic or semi-plastic condition as uniformly as possible. As is well known, this plastic condition occurs during the earlier stages of the coking operation. In 25 order that this plastic condition may be brought about as uniformly as possible, the intermediate partition walls are provided with heating ducts as before described, as are also the side walls of the retort so that 30 the material within the retort is heated not only from the sides and top but also the heat is radiated to the material from within the body of the material by the intermediate partition walls. As this material is being 35 carried by separate compressing floors and as these floors are connected together outside the retort so as to be simultaneously operated on, the compression of the material occurs simultaneously and equally at all 40 points along the heating ducts and the pressures on each side of the intermediate walls are balanced and the ducts are not disturbed nor imperiled by the exceedingly heavy pressures due to the compression. Owing to 45 the fact that the pressures are thus equalized, the intermediate walls may be made light enough in construction to quickly and effectively transmit the heat to the material so that uniformity of heat may be attained 50 and the material caused to assume a plastic or semi-plastic condition due to this distribution of heat. As the floors of the retort extend throughout the length thereof and carry the material from the charge end 55 to the discharge end, the retort is always filled with carbonaceous material and the heating ducts are, therefore, subjected to a uniform and balanced pressure and support throughout the retort. 60 The lip D' along the lower edge of the floors of the retort prevents leakage of the carbonaceous material which would tend to bind and prevent the free movement of the floor backward and forward. The lips extending into the channel or groove D² guide 65

the floor without binding on the walls or permitting the waste or leakage of the carbonaceous material.

As the heating ducts are intensely heated internally by products of combustion from burners or from the furnace and as their external surface is in contact with the cooler carbonaceous material within the retort there is produced an unequal heating effect upon the refractory material comprised in the side 70 walls and intermediate walls of the retort. This unequal heating effect causes unequal expansion tending to crack the refractory material forming the ducts so that if the tiles of refractory material are made solid, 75 it is difficult to maintain them gas tight, which is an essential thing in a by-product retort.

In order to provide as far as possible for the equal heating of the refractory material 80 in which the ducts are formed and for the proper expansion thereof, I preferably make the tiles of refractory material of the general shape indicated at B in the drawing Fig. 2, that is to say, each tile is formed with 85 a portion of a duct on its opposite sides so that each tile forms a part of two ducts. These tiles may thus be described generally as H shaped. In internally heating circular or 90 elliptical ducts, the tendency of the material 95 is to expand most at the point of highest temperature and as this point of highest temperature is on the internal surface of the duct the greater expansion is at the point of the shorter radius and hence the external 100 radius has a tendency to crack as it is not heated to the temperature of the internal radius.

It will be noted that tiles of refractory material are provided with ribs B² which 105 engage corresponding grooves in the adjacent tile, thus forming an interlocking connection between the adjacent tiles and at the same time permitting the adjustment of the tiles to compensate for unequal expansion. In the design as shown the refractory material is practically heated externally from both sides at its thinnest portion so that the equivalent of the external surface 110 of the tile is subjected to the highest temperature instead of the internal surface as would be the case if the tile were composed of a single block heated internally. The general effect of the heating of the block as shown is, therefore, to heat the two sides of 115 the refractory material and cause the expansion to take place more uniformly inward toward the retort cells in which direction the blocks are free to expand. As the blocks are thus uniformly heated, the tendency is not 120 to put a cross strain on the interlocking joints, but to cause a more uniform expansion in these interlocking joints. Thus it is possible to put a high temperature in the 125 ducts and to have the surface facing the cell 130

of the retort exposed to the cooling action of the coal or semi-formed coke without imposing severe contraction and expansion strains on the refractory material. The intermediate tiles forming the arch or roof of the retort are formed in the same general manner as the intermediate tiles in the walls. As the roof is supported by the side and intermediate walls, the tiles of the roof have a 5 keying effect owing to the weight and pressure transmitted from the arches to each set of ducts in the walls. By the provision of the expansion joints interlocking and held together as above described the bad effects 10 of unequal expansion are done away with.

While the apparatus above described is a suitable one for the purposes set forth, it will be apparent that the retort is susceptible of modification without departing from 15 the principle of my invention.

Having now particularly described and ascertained the nature of my said invention and in what manner the same is to be performed, I declare that what I claim is:

25. 1. A coke oven comprising in combination a substantially horizontal closed retort divided into a plurality of sections by intermediate walls of relatively light construction extending longitudinally through the

retort, means for feeding portions of carboniferous material simultaneously to each of the several sections of the retort, means for conveying the material forwardly in each of the several sections in the retort 35 simultaneously, and means for compressing simultaneously and equally the material in each of the several sections in the retort during the coking period.

2. A coke oven comprising in combination a substantially horizontal closed retort having comparatively heavy side walls, intermediate walls of relatively light construction extending longitudinally through the retort and dividing the retort into a plurality of sections, the side and intermediate 40 walls being provided with heating ducts, means for feeding portions of the material simultaneously to each of the sections of the retort, means for conveying the material forwardly in each of the several sections of 45 the retort simultaneously, and means for compressing simultaneously and equally the material in each of the several sections of the retort during the coking period.

LELAND L. SUMMERS.
